(57) **CLAIM**

The ornamental design for a shoe, as shown and described.

DESCRIPTION

FIG. 1 is a front, left and top perspective view of a shoe, showing my design.

FIG. 2 is a rear, right and bottom perspective view thereof.

FIG. 3 is a right side elevation view thereof.

FIG. 4 is a left side elevation view thereof.

FIG. 5 is a front elevation view thereof.

FIG. 6 is a rear elevation view thereof.

FIG. 7 is a top plan view thereof.

FIG. 8 is a bottom plan view thereof; and,

FIG. 9 is a front, left and top perspective view of the shoe in another state with the side zipper in an open position. The article shown is the design for a right foot shoe. The design also includes the article for the left foot which is not shown but is a mirror image of the article shown.

The broken lines depict portions of the shoe that form no part of the claimed design.

1 Claim, 9 Drawing Sheets
